ROTARY PRINTING PRESS

George J. Prager, Bayshore, N. Y., assignor, by
mesne assignments, to The Printcote Co., Inc.,
New York, N. Y., a corporation of New York

Application August 25, 1936, Serial No. 97,859

7 Claims. (Cl. 101—153)

This invention relates to new and useful improvements in a rotary press.

The invention has for an object the construction of a press as mentioned which is characterized by one or more printing units each including a form roll with which an intaglio blade may be associated when required. Specifically, it is proposed to arrange each intaglio blade so that it may be placed into and taken out of operation as required. When thus constructed each printing unit is adapted to print according to various printing methods such as surface printing, various modifications thereof, intaglio printing, and various modifications thereof.

More specifically, it is proposed to adapt the printing press so that it may do surface printing by the use of copper, brass, or steel milled surface rolls, hand cut or molded rubber rolls with wood or metallic cores, rubber plates mounted on wood or metal shells, curved electrotype plates, half tones mounted on wood or metal, and other variations thereof. With respect to the intaglio printing it is proposed to arrange the printing press so that it may be accomplished by using all the known types of intaglio rolls such as photo engraved rollers, milled intaglio rolls, pantograph, and other variations thereof.

Furthermore, in addition to printing each printing unit is adapted to various types of coating such as immersion coating or staining, surface blotch coating, intaglio pad coating, and others.

A further object of the invention is to adapt the various printing units for receiving various colors and various types of inks and other printing materials which heretofore could not successfully be handled on one machine. Heretofore various machines were provided each capable of performing one duty, as for example, laminating or varnishing and lacquering or aniline printing, oil printing, etc., each being limited to its specific individual purpose. In other instances machines have been designed which were capable of printing with certain particular types of plates and rollers in conjunction with certain particular types of inks or coloring material. For example, it would require the use of paste inks to print on electrotype plates or rolls. According to this invention it is possible to use inks or other printing materials of various consistencies to print on electrotype plates; even consistencies as thin as water. It is therefore a further object of this invention to provide a printing unit which permits the use of many types of inks such as oils, water, rotogravures,

anilines, lacquers, varnishes, pyroxylin, bronzes, micas, various adhesives for laminating, and other existing colors and materials many of which heretofore required special equipment.

Another one of the objects of this invention is to arrange the printing press so that it is capable of printing in various ways, for example:

1. One side—two colors.
2. Coating and printing on the same side.
3. Both sides coated.
4. Both sides printed.
5. Coat one side and print the other side.
6. One side—same color—both sides coated.

A still further object is to provide the printing press with a welded or similar structural steel frame and then to adjustably mount brackets thereon for the various parts of the printing press, which brackets are arranged in a manner to permit leveling. Thus, the necessity of leveling and "truing" the welded steel frame is eliminated.

A still further object of the invention resides in the provision of an arrangement which permits the form rolls to be easily removed and replaced. Heretofore it was customary to force the form rolls upon a supporting shaft under great pressure. It was then very difficult to remove the form roll. Specifically, the invention proposes an arrangement by which the form roll is releasably attached on the shaft in a simple and efficient manner.

Still further the invention contemplates an arrangement whereby each printing unit may be instantaneously shifted laterally and disengaged entirely from the pressure drum by moving a lever. Similarly, an arrangement is proposed by which the furnishing roll may be instantaneously shifted angularly out of contact with the form roll and the metal roll by a separate lever control.

Another object of the invention is the provision of heating drums mounted on the frame of the printing press at various locations and arranged to heat and dry the web of paper on either or both sides, as required.

Another one of the objects of the invention resides in the provision of a novel agitator for agitating the printing ink or other printing material within the ink pan.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a perspective view of a two color all purpose printing and tinting machine constructed 5 according to this invention.

Fig. 2 is a rear elevational view of Fig. 1.

Fig. 3 is a plan view of Fig. 1 illustrated with a top portion thereof broken away so that the lower parts are visible.

10 Fig. 4 is an end elevational view of Fig. 1 looking from the left hand end.

Fig. 5 is a fragmentary enlarged detailed view of the upper right hand portion of Fig. 2.

15 Fig. 6 is a fragmentary enlarged vertical sectional view taken on the line 6—6 of Fig. 2.

Fig. 7 is a schematic view of Fig. 1 illustrating the manner in which the paper web extends through the machine.

20 Fig. 8 is a longitudinal sectional view of one of the form rolls to show the details associated therewith.

The invention, as illustrated on the drawings and explained in this specification, is applied to one type of a two color printing machine. It 25 should be borne in mind that this is merely by way of illustration since it is just as applicable to a one color or other arrangement of two color, and also more than two color construction. The printing press, according to this invention, includes 30 a printing frame consisting of a pair of spaced parallel top members 10a and 10b supported upon vertical legs 11 which are braced by cross members 12. A pair of spaced parallel bottom members 13a and 13b are mounted upon the sides of 35 the legs 11. These different parts of the frame are welded together so as to form a rigid, solid and strong construction. At the centers of the top members 10a and 10b of the frame there are a pair of spaced apart brackets 14a and 14b. A 40 pressure rubber drum roll 15 is rotatively mounted between the brackets 14a and 14b. Above this pressure rubber drum roll there is rotatively mounted a heating drum 16. This drum is also rotatively supported between the brackets.

45 A color unit is mounted on each side of the rubber drum roll 15 and includes a form roll 17 which coacts with the rubber drum roll 15. More specifically, each color unit comprises the form roll 17, a furnishing roll 18 engaging the form roll, and a roll, such as a brass roll 19 or other metal or rubber roll engaging the furnishing roll.

50 Each color unit includes a pair of side brackets 20. These side brackets are slidably mounted within track elements 21 fixedly mounted on the members 10a and 10b. The approximate contours of the brackets 20 may be followed from a careful inspection of Fig. 5. Starting at the bottom portion, indicated by reference numeral 20a, the bracket extends upwards along the side portion 20b, then continues horizontally outwards into a portion 20c. From this portion the bracket extends along a top portion 20d to a slightly lowered top area 20e. From here the bracket extends upwards into a portion 20f. This portion 55 20f extends downward along the side 20g which terminates at the bottom in the bottom portion 20a. The brass roll 19 is rotatively mounted between the portions 20e of the brackets by reason of having a shaft 22 rotatively engaging the brackets 20. The form roll 17 is rotatively mounted between the portions 20f of the brackets. Slide elements 23 are slidably mounted in the tracks 21 immediately adjacent the outer sides 20b of the brackets 20. These slide elements 23, 60 at one of their ends, rotatively support the ends

of screws 24. These screws are threadedly engaged in brackets 25 fixedly attached upon the tracks 21. A rod 26 extends between the slides 23 and carries eccentrics 27 working in bearings 28 at the ends of links 29 which have their other ends pivotally connected by pins 30 with the sides 20b of the brackets. A handle 31 is fixed upon one of the ends of the rod 26.

5 The screws 24 may be rotated to move the slides 23 and the brackets 20 as a unit and so control 10 the pressure between the form roll 17 and the rubber drum roll 15. When desired, the handle 31 may be turned through a portion of a complete turn to cause the eccentrics 27 to move the brackets 20 relatively closer to the slides 23. 15 Thus, the form roll 17 may be moved out of contact with the rubber drum roll 15 without changing the adjustments of the screw 24.

The eccentrics 27 are arranged so that they are slightly turned past the dead centers when 20 the brackets 20 are in the remote positions from the slides 23 so that the slides 23 and the brackets 20 are locked in a rigid unit. It is for this reason that the pressure produced by the screws 24 may easily be transferred to the form roll 17 25 to engage against the pressure rubber drum roll 15.

Auxiliary slides 32 are slidably mounted upon the portions 20d of the brackets 20 and are rotatively associated with screws 33. These screws 30 threadedly engage through brackets 29' fixedly mounted on the portions 20d. Auxiliary brackets 35 are pivotally mounted by pins 36' to the slides 32. A rod 36 extends between the brackets 32 and fixedly carries eccentrics 37 which are associated with bearings 38 of links 39. These links are pivotally connected by pins 40 to the auxiliary brackets 35. A handle 41 is attached upon one end of the rod 36. Bearings 42 are vertically 35 slidably mounted upon the auxiliary brackets 35 40 and are associated with screws 42' threadedly engaging standards 43 fixedly mounted on the auxiliary brackets 35. The furnishing roll 18 is mounted between the bearings 42. The arrangement is such that the screws 33 may be turned to move the brackets 32 and so indirectly move the furnishing roll 18 against or from the form roll 17. The pivot 36' is slightly below the horizontal center line of the rod 36 so that the brackets 35 are past their dead center and there is no tendency for them to turn clockwise as viewed in Fig. 5. It is possible to pull down the brackets 35 at the outer sides of the pivots 36' so that the furnishing roll 18 is simultaneously moved out of contact with the brass roll 19 and the form roll 17. The screws 42' may be turned to control the pressure between the furnishing roll 18 and the brass roll 19.

An intaglio printing unit is associated with each 60 form roll 17 and is directed according to the proposed rotation of the form roll 17. For this reason in the right hand printing unit shown in Fig. 2, the intaglio blade is below the form roll 17, while in the left hand unit it is above the form roll. First considering the right hand unit, the intaglio printing unit consists of a pair of brackets 45 pivotally mounted at the points 46 on the brackets 20. These brackets 45 have shoe portions 47 resting against adjustment screws 48 which threadedly engage through lug portions 49 projecting from the brackets 20. The brackets 45 also have head portions 50. A shaft 51 is engaged between the head portions 50. This shaft carries a body 52 from which a blade 53 extends. The blade engages against the periphery of the 75

form roll 17. Counterweights 54 are mounted upon radial arms 55 projecting from the shaft 51 to force the blade 53 against the form roll 17 under desired pressures. These weights 54 frictionally engage the arms 55 so that they may be adjusted to various positions to change their moments, and thus the pressure exerted by the blade 53 against the form roll 17.

A grooved wheel 55 is fixed upon one end of the shaft 51 and is engaged by a blade 56 which is mounted on an arm 57. This arm is pivotally supported by a pintle 58 at its extremity. Intermediate of its ends it is formed with a slot 59 into which a pin 60 projects. This pin 60 is eccentrically mounted on a worm wheel 61. A worm pinion 62 engages this worm wheel and is fixedly mounted on the shaft 22 of the brass roll.

At one side of the machine (the near side as viewed in Fig. 1) a gear drive system is provided which may be traced by starting at the drive shaft 63. This drive shaft may be supplied with a pulley and a belt to obtain rotations from an outside force. A pinion 64 is mounted upon the drive shaft 63 and meshes with a pinion 65 rotatively supported on the bracket 146. This pinion 65 meshes with a gear 66 mounted upon pressure rubber drum roll 15. A gear 67 is mounted upon the shaft of the form roll 17 and meshes with the gear 66. This gear 67 also meshes with a gear 68 mounted upon the shaft of the furnishing roll 18. The gear 68 in turn meshes with a gear 69 mounted on the shaft 22 of the brass roll. It will thus be seen that the shaft 22 receives rotations indirectly from the drive shaft 63 and in turn rotates the worm wheel 61 which causes the arm 57 to oscillate, which in turn oscillates the shaft 51 and thus the blade 53.

Now referring to the print unit at the left in Fig. 2 it should be noted that there are a pair of top arms 70 which are pivotally supported by pintles 71 upon lugs 72 projecting from the top portions 20f of the brackets 20. Screws 73 are threadedly associated with the arms 70 and abut lugs 74 upon the portions 20f of the brackets 20. Thus, the arms 70 may be supported in various adjusted positions. The free ends of the arms 20 support a shaft 75 upon which an intaglio unit is mounted. This intaglio printing unit consists merely of a body portion and blade similar to the parts 52 and 53 previously referred to. The blade acts against the print roll. Adjustable weights 76 are mounted upon radial arms 77 projecting from the shaft 75 to force the blade against the form roll with suitable pressure. At one end of the shaft 75 there is a grooved wheel 78 which engaged by the forked end of an arm 79. This arm has a boss 80 at its bottom end which slidably engages upon a stud 81 mounted on the bracket 20. A grooved wheel 82 is associated with the lower end of the arm 79 and is engaged by the end of an arm 82' which is pivotally mounted by a pintle 83 at its remote end. This pintle engages a bracket 84 projecting from the bracket 20. Intermediate of its ends the arm 82' is formed with a slot 59 which is engaged by a pin 60 projecting from a worm wheel 61 engaging a worm 62 upon the shaft 22 of the brass roll 19.

The print unit at the left in Fig. 1 is driven by gears 67, 68 and 69 as previously described relative to the unit at the right. Each of the gears 68 mesh with the said gear 69 on the shaft 22. Each gear 69 is utilized to drive an ink stirrer

for the printing unit. There is a belt 87 extending from a pulley coaxial with the gear 69 and engaging a pulley 88 upon a shaft 89 of a stirrer mechanism. This shaft 89 is supported by brackets 90 upon the stationary brackets 29. The shaft 89 supports a tubular member 91 formed with a continuous thread 92 extending from one end portion to the other end portion, and back again. A follower 93 is mounted on the tubular member 91 and has a pin 94 engaging thread 92. This follower 93 is steadied by a forked-shaped portion 93' engaging a stationary rod 94' fixed on a guard 95 supported across the top of the tube 91. An arm 96 projects from the follower 93 and engages into an ink pan 15 97. This ink pan is supported by rods 98 fixed to the brackets 20. The brass roll 19 extends into the ink pan 97, as clearly shown in Fig. 6. A roll of paper 99 is mounted upon a rod 100 indirectly supported upon one of the ends of the members 13a and 13b. Specifically, one of the ends of the rod 100 is mounted on a bracket 101 slidably mounted in a track element 102. A screw 103 is threadedly associated with the track element 102 and rotatively with the bracket 101 which permits adjustment of the rod so that the web of paper from the roll 99 may unwind in a "true" manner.

The other end of the rod 100 is merely rotatively supported and connected with a brake device 100a. From the roll 99 there extends a web portion 99a which engages through the machine as hereinafter further described, and finally terminates in a receiving roll 99'. This receiving roll 99' is mounted upon a shaft 100' which at one end is adjustable by a mechanism consisting of the bracket 101, the track 102, and the screw 103 as previously described. The other end of the shaft 100' is associated with a drive device which includes a brake structure. Specifically, this brake device includes a belt 105 which extends upwards over a wheel 106 mounted upon one end of the shaft of one of the form rolls 17. There is a pressure roll 107 upon arms 108 adapted to be moved by a screw 109. This pressure roll 107 engages a portion of the belt 105. The belt also engages over a roll 110. This roll 110 is associated with a gear system 111, the last gear of which is fixed upon the rod 100'. 40

The web of paper, starting from the supply roll 99, continues into the said web portion 99a and then over several tensioning rods 115. These tensioning rods are supported between blades 116 attached to the top members 13a and 13b. The web then continues over a guiding rod 116' supported between the brackets 14a and 14b. It then passes up between the pressure rubber drum 15 and one of the form rolls 17. It then extends over the heating drum 16, and continues down between the other form roll 17 and the pressure rubber drum roll 15. From this point there is a web portion 99b which extends downwards over another heating drum 117 which is rotatively supported on a standard 118 supported on the members 13a and 13b of the frame of the machine. 65 From the heating drum 117 a web portion 99c extends upwards over another heating drum 119 which is rotatively supported in brackets 120 mounted upon the legs 11 of the frame of the machine. From the heating drum 119 a web portion 70 extends over guide bars 121 and 122 to a web portion 99d which terminates upon the roll 99'. A belt 123 extends over a pulley on the shaft 63 and a pulley 124 on the shaft of the heating drum 119. A chain or gear drive may be substi- 75

tuted. At the other side of the machine there is a belt 125 which is connected between pulleys 126 mounted on the shafts of the heating drums 117 and 119. Each of the heating drums merely 5 comprises a hollow cylinder rotatively mounted and connected by a swivel connection 127 to a steam inlet pipe. The heating drum 116 is driven by a gear drive consisting of gear 130 meshing with gear 66 and fixed on shaft 131 provided with 10 a gear 132 meshing with a gear 133 fixed coaxial with said drum 116.

The frame of the printing press which is composed of the members 10a and 10b, the legs 11, the cross members 12, and the bottom members 13 and 13b are welded together or secured together in any other inexpensive manner even though the construction is quite rough. In order that the operative parts of the printing press be true and accurate a leveling arrangement is provided 15 for each of the parts which come into contact with portions of the rough frame of the machine. For example, the leveling arrangement is applied to the tracks 21, the brackets 14a and 14b, etc. Specifically, the leveling arrangement comprises 20 several set screws 135 (see Fig. 5) engaged through flange portions of the member 10a or other portion of the welded frame and abutting against the track 21 or other true member interposed therebetween such as a mounting plate 136. 25 The mounting plate 136 is then securely bolted in its level position by a plurality of bolts 137. The tracks 21 are secured to the mounting member 136.

An arrangement is also provided for supporting 30 each of the form rolls 17 so that they may be quickly and easily removed and replaced. This is accomplished by constructing each of the form rolls 17 of cylindrical form adapted to be loosely mounted on a supporting shaft 140. A shoulder 35 bushing 141 is permanently mounted on a portion of the shaft 140 and supports one end of the form roll 17. The other end is supported by a similar bushing 141'. This latter bushing is removably held in position by a set screw 142. Furthermore, 40 this latter bushing and the adjacent end of the form roll 17 is provided with inter-engaging teeth 143 to hold them against relative rotations. The form roll 17 may be easily removed by first removing the screws 142 and then the bushing 141', and finally slipping the print roll from its position. An arrangement is also provided whereby 45 the form roll 17 may be easily adjusted for longitudinal and lateral registration as is required when more than one color is printed. The shaft 140 has a reduced end portion 140a at one end, and at the other end a reduced portion 140b. The portion 140a slidably engages in a bushing 144 which is rotatively supported by a ball bearing 145 on the bearing housing 146, which in turn 50 is supported on the bracket 20. The portion 140a has a threaded section 140' which is provided with a nut 147 which engages against one end of the bushing construction 144. A cap screw 148 55 threadedly engages into the end of the shaft portion 140a and acts against a washer 149 resting against the bushing structure 144. When the cap screw 148 and the nut 147 are loosened the shaft 140 may be shifted and so the lateral registering accomplished.

The shaft portion 140b is provided with a bushing construction 150 which is associated with a ball bearing 151 supported by a housing 152 which is capable of being mounted on the other supporting bracket 20. The drive gear 68 is loose 70 upon the shaft portion 140b but is connected by a 75

pin 153 with a member 154 adjacent it and also loose on the shaft portion 140b. This member 154 supports a worm 155 which meshes with a worm wheel 156, slidably mounted on the shaft portion 140b by a key device 157. A cap screw 168 5 engages through a washer 169 acting against the member 156. The cap screw 168 threadedly engages into the end of the shaft portion 140b. The gear 68 rests against the edge of the bushing 150. The cap screw 168 is therefore capable of being 10 screwed down and assists in holding the shaft portion 140b fixed relative to the gear 68. When required, the screw 168 may be loosened and the worm 155 turned to turn the worm wheel 156 and so the shaft 140 relative to the gear 68. Thus 15 longitudinal registering is accomplished.

While I have illustrated and described my invention with some degree of particularity, I realize that in practice various alterations therein may be made. I therefore reserve the right and privilege of changing the form of the details of construction or otherwise altering the arrangement of the correlated parts without departing from the spirit or the scope of the appended claims.

Having thus described my invention, what I 25 claim and desire to secure by Letters Patent, is:

1. In a printing press, a color unit, comprising a pair of parallel spaced track elements, slides on said track elements, side brackets slidably mounted on said track elements and including 30 base portions engaging said track elements, an outer top portion, and an inner top portion, a furnishing roll rotatively mounted between said side brackets at points intermediate of said outer and inner top portions, a form roll rotatively mounted between the inner top portions of said side brackets, auxiliary slides slidably mounted on the outer top portions of said side brackets, auxiliary brackets pivotally mounted on said auxiliary slides, an intermediate furnishing roll rotatively and adjustably on said auxiliary brackets and engageable against said form roll and said furnishing roll, means cooperative with said auxiliary brackets for adjusting the pressure between said intermediate furnishing roll and said furnishing roll, eccentric means cooperative between said auxiliary brackets and auxiliary slides for holding said parts fixed and movable from said fixed position, adjustment means cooperative with said side brackets and auxiliary slides for controlling the pressure of said intermediate furnishing roll and said print roll, eccentric means cooperative between said auxiliary brackets and auxiliary slides for holding these parts fixed and movable from said fixed positions, and adjustment means cooperative with said slides for adjusting the form roll relative to said track elements for controlling the pressure between said form roll and a pressure roll.

2. In a printing press, a color unit, comprising a pair of spaced side brackets slidably supported, a form roll rotatively mounted between said side brackets, means for holding said side brackets in various fixed positions to engage said form roll against a pressure drum under various pressures, a furnishing roll rotatively mounted between said side brackets, auxiliary slides slidably mounted on said side brackets, an intermediate furnishing roll rotatively mounted and supported on said auxiliary slides and engageable simultaneously with said furnishing roll and with said form roll, means for holding said auxiliary slides in various fixed positions to engage said intermediate furnishing roll against one of said rolls under various pressures, and means for holding said inter- 75

mediate furnishing roll adjustably on said auxiliary slides to engage said intermediate furnishing roll against the other of said rolls under various pressures.

5 3. In a printing press, a color unit, comprising a pair of spaced side brackets slidably supported, a form roll rotatively mounted between said side brackets, means for holding said side brackets in various fixed positions to engage said form roll 10 against a pressure drum under various pressures, a furnishing roll rotatively mounted between said side brackets, auxiliary slides slidably mounted on said side brackets, an intermediate furnishing roll rotatively mounted and supported 15 on said auxiliary slides and engageable simultaneously with said furnishing roll and with said form roll, means for holding said auxiliary slides in various fixed positions to engage said intermediate furnishing roll against one of said rolls 20 under various pressures, and means for holding said intermediate furnishing roll adjustably on said auxiliary slides to engage said intermediate furnishing roll against the other of said rolls under various pressures, said means for holding 25 said side brackets in various fixed positions comprising slides slidably mounted, screws rotatively connected with said slides and threadedly engaging through stationary members, and eccentric means cooperative between said slides and 30 side brackets for holding said parts fixed and movable from said fixed positions.

4. In a printing press, a color unit, comprising a pair of spaced side brackets slidably supported, a form roll rotatively mounted between said side 35 brackets, means for holding said side brackets in various fixed positions to engage said form roll against a pressure drum under various pressures, a furnishing roll rotatively mounted between said side brackets, auxiliary slides slidably mounted 40 on said side brackets, an intermediate furnishing roll rotatively mounted and supported on said auxiliary slides and engageable simultaneously with said furnishing roll and with said form roll, means for holding said auxiliary slides 45 in various fixed positions to engage said intermediate furnishing roll against one of said rolls under various pressures, and means for holding said intermediate furnishing roll adjustably on said auxiliary slides to engage said intermediate 50 furnishing roll against the other of said rolls under various pressures, said intermediate furnishing roll being supported on said auxiliary slides with brackets, said latter brackets being pivotally mounted on said auxiliary slides, said intermediate furnishing roll being rotatively supported 55 on said latter brackets, and eccentric means cooperative between said latter brackets and said auxiliary slides for holding said parts fixed and pivotal from said fixed positions, said means for holding said intermediate furnishing roll adjustably on said auxiliary slides comprising blocks slidably mounted on said latter brackets, and screws rotatively connected with said blocks and threadedly engaging through stationary members 60 mounted on said latter brackets.

5. In a printing press, a color unit, comprising a pair of spaced side brackets slidably supported, a form roll rotatively mounted between said side brackets, means for holding said side brackets in various fixed positions to engage said form roll 65 against a pressure drum under various pressures, a furnishing roll rotatively mounted between said side brackets, auxiliary slides slidably mounted on said side brackets, an intermediate furnishing roll rotatively mounted and supported 70 on said auxiliary slides and engageable simultaneously with said furnishing roll and with said form roll, means for holding said auxiliary slides in various fixed positions to engage said intermediate furnishing roll against one of said rolls under various pressures, means for holding said intermediate furnishing roll adjustably on said auxiliary slides to engage said intermediate furnishing roll against the other of said rolls under various pressures, brackets pivotally mounted on said side brackets, means for holding said latter brackets in various adjusted positions, and a blade supported on said latter brackets and engageable 75 with a form roll for intaglio printing.

said intermediate furnishing roll adjustably on said auxiliary slides to engage said intermediate furnishing roll against the other of said rolls under various pressures, said intermediate furnishing roll being supported on said auxiliary 5 slides with brackets, said latter brackets being pivotally mounted on said auxiliary slides, said intermediate furnishing roll being rotatively supported on said latter brackets, and eccentric means cooperative between said latter brackets 10 and said auxiliary slides for holding said parts fixed and pivotal from said fixed positions, said means for holding the auxiliary slides in various fixed positions comprising said screws rotatively connected with said auxiliary slides and threadedly engaging through stationary members.

6. In a printing press, a color unit, comprising a pair of spaced side brackets slidably supported, a form roll rotatively mounted between said side brackets, means for holding said side brackets 20 in various fixed positions to engage said form roll against a pressure drum under various pressures, a furnishing roll rotatively mounted between said side brackets, auxiliary slides slidably mounted on said side brackets, an intermediate furnishing 25 roll rotatively mounted and supported on said auxiliary slides and engageable simultaneously with said furnishing roll and with said form roll, means for holding said auxiliary slides in various fixed positions to engage said intermediate furnishing roll against one of said rolls under various pressures, and means for holding said intermediate furnishing roll adjustably on said auxiliary slides with brackets, said latter brackets being pivotally mounted on said auxiliary slides, said intermediate furnishing roll being rotatively supported 30 on said latter brackets, and eccentric means cooperative between said latter brackets and said auxiliary slides for holding said parts fixed and pivotal from said fixed positions, said means for holding said intermediate furnishing roll adjustably on said auxiliary slides comprising blocks slidably mounted on said latter brackets, and screws rotatively connected with said blocks and threadedly engaging through stationary members 35 mounted on said latter brackets.

7. In a printing press, a color unit, comprising a pair of spaced side brackets slidably supported, a form roll rotatively mounted between said side brackets, means for holding said side brackets in various fixed positions to engage said form roll 40 against a pressure drum under various pressures, a furnishing roll rotatively mounted between said side brackets, auxiliary slides slidably mounted on said side brackets, an intermediate furnishing roll rotatively mounted and supported on said auxiliary slides and engageable simultaneously with said furnishing roll and with said form roll, means for holding said auxiliary slides in various fixed positions to engage said intermediate furnishing roll against one of said rolls under various pressures, means for holding said intermediate furnishing roll adjustably on said auxiliary slides to engage said intermediate furnishing roll against the other of said rolls under various pressures, brackets pivotally mounted on said side brackets, means for holding said latter brackets in various adjusted positions, and a blade supported on said latter brackets and engageable 45 with a form roll for intaglio printing.
